UNITED STATES PATENT OFFICE.

FRANÇOIS V. ISOIRE DIT PROVENÇAL, OF ST. FREDERIC, QUEBEC, CANADA.

CAR-COUPING.

SPECIFICATION forming part of Letters Patent No. 309,058, dated December 9, 1884.

Application filed July 26, 1884. (No model.)

To all whom it may concern:

Be it known that I, FRANÇOIS VICTOR ISOIRE DIT PROVENÇAL, a citizen of Canada, residing at St. Frederic, in the county of Beauce, 5 in the Province of Quebec, Canada, have invented certain new and useful Improvements in Car-Couplings; and I do hereby declare the following to be a full, clear, and exact description of the same.

10 The object of my invention is the construction of a device by which any given car in a train of cars can be coupled or uncoupled from one given point—such as the tender of the engine, the brake-van, or any other point 15 at which the operating-gear is located.

My improved device consists, mainly, of a shaft journaled to the under side of the car-floor, and to one side thereof, and provided with a tongue-and-fork coupling, so as to 20 couple automatically into line when the cars are brought together. This shaft is provided with a cam or thumb set at a different angle on each shaft, and so placed as to lift the coupling-pin, which takes the form of a hook 25 pivoted over and outside the center of the shaft and at right angle thereof. The shaft or line of shafts is operated by a crank and a train of wheels upon the tender, the brake-van, or other suitable point in the train. A 30 device regulating the position of the link is also provided, consisting of a spring lift holding up the projecting end of the link, and a projecting bar on the opposite car engaging the said lifter and depressing the same to lower 35 the link if demanded by the relative position of the two draw-heads.

In the drawings, Figure 1 is a plan of a car-platform with the adjoining tender and part of another car. Fig. 2 is an elevation of the 40 same. Fig. 3 is an end view of a car, showing the coupling-pin lifted and the link uncoupled.

A A are car-platforms, and B is the tender.

C are the draw-heads, and D the coupling-links, all of the ordinary construction.

E are shafts journaled to the under side of the car-floor and near the side of the car, one end having a fork, e, with flaring mouth, and the other end a flat tongue, e', intended to

enter the fork e, and automatically coupling 50 the same rotatively. One of these shafts is placed at each side of the car, so that the ends of cars may be reversed.

E' is a cam or thumb placed near each end of each shaft, and each secured to the shaft at 55 a different angle with any other in the same train.

F is the coupling-pin, forming the point of a hook pivoted outside of the shaft E, and over the same and the cam E'. The shaft, which 60 is journaled to the tender, (or to the car or point from which it is intended to operate the same,) carries a spur-wheel, G, geared by a train of wheels, H, to a pinion, I, upon the axle of which is secured a hand-crank, I'. 65

K is a spring lifting-bar holding up the link, and L is an adjusting-bar on the opposite car, secured rigidly, and bent to engage the top of the projecting arm k and to depress it, so as to allow the link to drop into 70 the proper position to enter the approaching draw-head.

The device operates as follows: All the cars being coupled, the shafts E are also coupled rotatively, and the entire line of shafts in one 75 train may be rotated by the stoker or other operative by means of the crank I', and in the course of one complete revolution of the line of shafts E all the coupling-pins F will have been raised and dropped again in succession. 80 When the pin F is raised, the link is uncoupled and the two corresponding cars may be moved apart.

If any particular car is to be uncoupled, a person will watch the corresponding coupling-pin, and when raised will signal to the person turning the handle I', who, upon receiving the signal, will cease to work the crank, as the car in question is then uncoupled and may be moved off. In coupling it is only 90 necessary to see that the crank is turned into such a position that none of the coupling-pins are raised out of engagement with the link.

Having thus described my invention, what I 95 claim is—

The shafts E, coupling automatically by means of forked and tongued ends into a line

along the whole length of the train, and having cams E' set at different angles from each other, said line rotated at will by means of a crank and intermediate of wheels located at 5 any suitable point in the train, and lifting the coupling-pins F, pivoted over the said cams, in combination with the draw-heads C, links D, spring lifts K, and adjusting-bars L,

substantially as described, and for the purpose set forth.
